UNITED STATES PATENT OFFICE

AUGUST M. BECKER, OF NEW YORK, N. Y.

GUIDE FINGER FOR MACHINES FOR COATING WEBS WITH ADHESIVES

Application filed May 17, 1929. Serial No. 363,816.

This invention relates to a new and improved guide finger for machines for coating adhesives in liquid form to the surface of a web or sheet of material and this improved design is particularly well adapted to the type of machine shown in my U. S. Letters Patent No. 1,435,197 dated November 14, 1922 and No. 1,493,061 dated May 6, 1924 and to which reference may be had for the particular application of my present invention.

The object of my invention is to provide guide fingers which are easily removable, without disturbing any working parts of the machine, thereby saving the idle fingers from being unnecessarily in contact with the adhesive material on the surface of the drum.

Another object of my invention is to provide an economical arrangement for the contact edge, subject to wear, by providing a detachable blade, whereby a long useful life is assured.

With these objects in view, which will fully appear as the invention is described, it being understood, that many changes may be made in the size, shape and proportion of the parts as more fully pointed out in the claim, after being set forth in the description and illustrations accompanying the same, without departing from the spirit of the invention.

In the accompanying drawings I have illustrated my invention, and in the same:

Fig. 1 is a cross section of a machine of this class.

Fig. 2 is a top view of the same.

Fig. 3 is a side elevation of the guide finger without the detachable blade.

Fig. 4 is a side elevation of the blade.

Fig. 5 is a top view of the guide finger assembled with the blade.

Referring to the drawings, 1 indicates a receptacle or tank for holding the adhesive material 2, which is kept in a warm condition. A rotary adhesive-distributing drum or cylinder 3 is mounted in the tank, to carry the adhesive upward in a thin coating and transfer the adhesive in a layer to the underside of the web or sheet of material 4, which is moved transversely across the upper surface of the drum in close contact therewith for this purpose.

After passing under the guide plates 5, the coated web 4, is moved onto a series of inclined swinging guide fingers 6, which freely swing in a vertical plane on the rod 7. The guide fingers are arranged at suitable intervals along the length of the drum, and any number of them may be placed in operation, as desired.

The guide finger 6, is formed in the shape as shown in Fig. 3. For mounting on the rod 7, it is provided with a slot 8, with semi circular top to conform to the cross section of the rod 7, and permit a swinging movement in a vertical plane, being sufficiently wide to assure a good seat on the said rod 7. The guide finger has its free end 9, beveled and is equipped with a fixed dowel pin 10 and threaded hole 11, located to correspond with the holes 12, in the blade 13. The blade itself is in the form of a rhombus, made of thin material, to provide a minimum of contact of surface between the same and the web, so that there is little chance of much of the adhesive being retained by the guide fingers; having four equal sides lettered *a*, *b*, *c*, *d*. The above mentioned two holes 12, are located on the longer diagonal, equally distant from the shorter diagonal, thereby making it possible the use of any side of the rhombus, to be in contact with the adhesive on the drum.

Consider first the side *a*, as the working surface, being worn so as to become inoperative, by removing the screw 14, and turning blade 13, around the longer diagonal, side *b*, comes exactly in place of the previous location of side *a*, and thereby a new working edge is provided, the blade 13, being held in place by screw 14, and fixed dowel pin 10. The same way sides *c*, and *d*, provide two more working edges, resulting in a very economical long life of blades.

Having thus described my invention, what I claim and desire to secure by Letters Patent is:

In an adhesive coating machine provided with a rotating drum and with a plurality of pivoted blade holders, means permitting removal of each blade holder and blade individually while said drum is rotating; said

means comprising an open slot at one end of each blade holder for detachably engaging with a pivot on said machine and said blade holders being also provided with means for

5 removably attaching blades thereto.

In testimony whereof I affix signature.
AUGUST M. BECKER.
